CLAIM

The ornamental design for a multi-purpose tool kit, as shown and described.

DESCRIPTION

FIG. 1 is a perspective view of a multi-purpose tool kit showing my new design in an open position of use; FIG. 2 is a top plan view thereof; FIG. 3 is a bottom plan view thereof; FIG. 4 is a left side elevational view thereof; FIG. 5 is a right side elevational view thereof; FIG. 6 is a front plan view thereof; FIG. 7 is a rear plan view thereof; FIG. 8 is a perspective view of the multi-purpose tool kit of FIG. 1 in a closed position of use; FIG. 9 is a top plan view thereof; FIG. 10 is a bottom plan view thereof; FIG. 11 is a left side elevational view thereof; FIG. 12 is a right side elevational view thereof; FIG. 13 is a front plan view thereof; and, FIG. 14 is a rear plan view thereof. The broken lines shown in the drawings are included for the purpose of illustrating unclaimed portions of the multi-purpose tool kit and form no part of the claimed design.

1 Claim, 14 Drawing Sheets
